UNITED STATES PATENT OFFICE.

GUSTAV E. SCHNEIDER AND ARTHUR B. SCHNEIDER, OF CHICAGO, ILLINOIS, ASSIGNORS TO ROTO TRAY COMPANY, A CORPORATION OF ILLINOIS.

DESIGN FOR A SMOKER'S TRAY.

Application filed June 18, 1928. Serial No. 27,191. Term of patent 3½ years.

To all whom it may concern:

Be it known that we, GUSTAV E. SCHNEIDER, and ARTHUR B. SCHNEIDER, citizens of the United States, both residing at Chicago, in the county of Cook and State of Illinois, whose post-office addresses are ¾ Schneider Electric & Manufacturing Co., 312 North Sheldon Street, Chicago, Illinois, have invented a new, original, and ornamental Design for a Smoker's Tray, of which the following is a specification, reference being had to the accompanying drawing, forming a part thereof.

Fig. 1 is a perspective view showing our new design.

Fig. 2 is a side elevational view of the same, and

Fig. 3 is an end elevational view of the same.

We claim:

The ornamental design for a smoker's tray as shown.

Signed at Chicago, county of Cook, State of Illinois this 7th day of June, A. D., 1928.

GUSTAV E. SCHNEIDER.
ARTHUR B. SCHNEIDER.
